UNITED STATES PATENT OFFICE.

HILBERT L. FALK, OF NEW ORLEANS, LOUISIANA.

TELEPHONE TRANSMITTER.

Application filed September 30, 1921, Serial No. 504,445. Renewed October 9, 1924.

To all whom it may concern:

Be it known that I, HILBERT L. FALK, a citizen of the United States, residing at New Orleans, parish of Orleans, State of Louisiana, have invented a new and useful Telephone Transmitter, of which the following is a specification.

My invention consists of a novel construction of a transmitter, which is especially 10 adapted for long distance or radio telephony, wherein the liability of any of the elements, under high amperage, fusing during long continued, uninterrupted service is entirely eliminated, as my novel device, is 15 not affected by dampness and in addition gives perfect articulation under any and all current variations.

In carrying out my invention, I employ a suitable casing for the various elements 20 appertaining to my invention, which are assembled therein in such a manner, that any and all of the same are readily accessible for the purpose of regulating the pressure upon the diaphragm, the silicon granules, 25 and their adjuncts, so that perfect regulation for all requirements can be readily attained.

To the above ends my invention consists 30 of a novel construction of outer casing, a diaphragm, and a supporting frame, whereby the cup containing the silicon granules, the buttons and their adjuncts can be readily supported and adjusted with respect to said frame and diaphragm.

It further consists of other novel features 35 of construction, all as will be hereinafter fully set forth and pointed out in the claims.

For the purpose of illustrating my invention, I have shown in the accompanying 40 drawings, a form thereof which is at present preferred by me, since the same will give in practice satisfactory and reliable results, although it is to be understood that the various instrumentalities of which my 45 invention consists may be variously arranged and organized and that my invention is not limited to the precise arrangement and organization of these instrumentalities as herein shown and described.

Figure 1 represents a vertical, sectional view of a transmitter embodying my invention.

Figure 2 represents on an enlarged scale 55 a perspective view in detached position of the supporting frame, whereby the cup con-

taining the silicon granules and their adjuncts is supported.

Figure 3 represents on an enlarged scale 60 in detached position, a sectional view of the cup employed.

Figure 4 represents a perspective view of the silicon button and its mica plate with the threaded stem projecting therefrom.

Figure 5 represents on an enlarged scale, 65 a sectional view of a preferred form of the diaphragm employed.

Similar numerals of reference indicate corresponding parts.

1 designates my novel construction of transmitter, the same comprising the mouth 70 piece 2, which is secured to the body 3, which is composed of the outer annular wall 4 and the inwardly projecting walls or flanges 5 and 6, forming a chamber 7, in which is contained the washer 8 of vul- 75 canized fibre or the like having the central opening 9. Against the washer 8 is secured the gasket 10 preferably of soft rubber having the central opening 11. Against the gasket 10 is placed the diaphragm 12, on 80 the opposite side of which is the rubber gasket 13, which has the central hole 14 therethrough. Against the gasket 13 bears the flanges 15 of the frame 16, whose construction will be understood from Figure 2, 85 which flanges are engaged by the screws 17. The frame 16 is provided with the walls 18 and 19, and in said wall 19 is threaded the adjusting screw 20, whose end bears on the rear stem 21, projecting rearwardly 90 from the cup 22, composed of the base 23 and the annular wall 24 as will be under- 95 stood from Figure 3. The rear stem 21 passes freely through the hole 37 of the frame 16.

25 designates a carbon plate or button, against which are the silicon granules 26, against which is the front silicon plate or button 27, from which projects the threaded stem 28. 29 designates a sheet of mica or 100 other insulation fastened to the front silicon button 27. 30 designates a nut on the stem 28 bearing on the back of the diaphragm 12.

31 designates the outer adjusting nut on the stem 28. 32 designates the back casing 105 which has the terminal of the line 33 secured to it in any suitable manner, while the terminal of the line 34 passes through said back casing at the point 35 and through the hole 36 of the frame 16 and is secured to 110

the stem 28. I preferably employ as the diaphragm 12, the composition diaphragm seen in Figure 5, wherein 38 designates a cured skin, coated on each side with a coating of liquid glass 39, one of said liquid glass surfaces being secured to the soft iron diaphragm, 40. This composition diaphragm, which forms the subject matter of a contemporaneously pending application 10 filed by me on the 19th day of September, 1921, Serial #501,860, I have found in practice to give results, superior to any other construction, with which I am familiar, and I preferably employ the same although of course other diaphragms may be employed without departing from the spirit of my invention.

It will be seen from Figure 1 that a very accurate adjustment of the principal elements of my invention can be attained by the manipulation of the screw 20 and the nuts 31 and 30, whereby the pressure between the diaphragm 12, the buttons 27 and 25 and the silicon granules 26 can be adjusted with great exactness, and I have found from practical use that the employment of the silicon granules 26 eliminates the possibility of fusing under high amperage, and during long continued service 30 and gives much superior results over carbon grains, which are easily fused by high amperage, especially during long continued, uninterrupted service, said carbon grains being also under certain working conditions affected by dampness.

If desired the button 25 may also be of silicon, and galena grains may be employed in lieu of the silicon grains 26, since silicon buttons are harder than carbon, and will not fuse and their polish is not affected by moisture or heat and will stand a much higher polish than the carbon buttons commonly employed. My novel transmitter has been found in practice to be far more sensitive than the carbon type, and by reason of the pressure adjusting devices, permits of perfect regulation for all needs, and is especially adapted for radio telephony, since it is able to withstand any voltage which may be met under commercial requirements.

It will be further apparent that by my construction the outer periphery of the diaphragm 12 is resiliently supported between the soft rubber gaskets 10 and 13, so that the diaphragm particularly when constructed as seen in Figure 5 will be very sensitive and responsive to the sound waves or undulations acting thereon.

It will now be apparent that I have devised a novel and useful transmitter for telephone for submarine, radio and other purposes, which embodies the features of advantage enumerated as desirable in the statement of the invention and the above description, and while I have in the present in-

stance, shown and described a preferred embodiment thereof which will give in practice satisfactory and reliable results, it is to be understood that the same is susceptible of modification in various particulars without departing from the spirit or scope of the invention or sacrificing any of its advantages. 70

Having thus described my invention, what I claim as new and desire to secure by Letters Patent, is:—

1. In a transmitter, a diaphragm resiliently supported at its outer periphery, a body of silicon granules supported at the rear of said diaphragm, means for exerting 80 pressure upon said body of granules, a front silicon button bearing on the front portion of said granules, a threaded stem projecting from said front button through said diaphragm, an adjusting nut on the outer portion of said stem and bearing on said diaphragm, and a nut on said stem in the rear of said diaphragm.

2. In a transmitter, a diaphragm resiliently secured at its outer periphery, a cup supported at the rear of said diaphragm, silicon granules in said cup, a button at the bottom of said cup, a silicon button at the outer portion of said cup, a non-conductor attached to the outer silicon button, means at the rear of said transmitter for exerting pressure on said cup and means common to said diaphragm and front silicon button for exerting pressure on the latter.

3. In a transmitter, a diaphragm resiliently secured at its outer periphery, a cup supported at the rear of said diaphragm and open at its front end, silicon granules in said cup, a button at the bottom of said cup, a silicon button at the outer portions of said cup, a sheet of mica attached to said outer silicon button, a frame for retaining said cup in position, an adjusting screw passing through said frame and adapted to vary the pressure on the rear of said cup, a threaded stem common to the front outer silicon button in said cup and said diaphragm, an adjusting nut on said stem bearing on the front of said diaphragm, and a nut on said stem in the rear of said diaphragm.

4. In a transmitter, a diaphragm resiliently supported at its outer periphery, a cup located at the rear of said diaphragm, silicon granules in said cup, a frame for supporting said cup, the latter having a rear stem passing through said frame, a threaded adjusting screw mounted in said frame and bearing on said stem, a button in the bottom of said cup upon which said granules are supported, a front silicon button in said cup, a sheet of mica supported upon said silicon button, a threaded stem projecting from the latter and passing through said diaphragm, an adjusting nut on the outer portion of said stem and bear-

ing on said diaphragm and a nut on said stem in the rear of said diaphragm.

5. In a transmitter, a body having inwardly projecting flanges, a diaphragm resiliently supported between said flanges, a frame having its ends also supported between said flanges, a cup supported by said frame and having a rear stem positioned therein, an adjusting screw for said stem, a 10 button in the bottom of said cup, silicon granules in said cup, a front button of silicon in said cup, a threaded stem projecting from said front button and passing through said diaphragm and an adjusting nut on said stem and bearing on said diaphragm, the latter being composed of a cured skin, liquid glass secured to each surface of said skin, and soft iron secured to one of said liquid glass surfaces.

20 6. In a transmitter, a diaphragm resiliently supported at its outer periphery, a cup open at its front end and supported in the rear of said diaphragm, silicon granules in said cup, a silicon button in the front 25 of said cup and contacting with said silicon granules, adjusting devices common to said silicon button and said diaphragm, a button in the bottom of said cup, and means for exerting pressure on the rear of said silicon 30 granules.

7. In a transmitter, a diaphragm resiliently supported at its outer periphery, a cup open at its front and supported at the rear of said diaphragm, a button at the 35 bottom of said cup, a silicon button in the front of said cup, silicon granules supported in said cup between said buttons, means for exerting pressure on the rear of said silicon granules, and adjusting devices common 40 to said front silicon button and said diaphragm for adjusting the pressure on the front of said silicon granules.

8. In a transmitter, a diaphragm resiliently supported at its outer periphery, a 45 cup open at its front and supported at the rear of said diaphragm, a button at the bottom of said cup, a silicon button in the front of said cup, silicon granules supported in said cup between said buttons, means for exerting pressure on the rear of said silicon granules, and adjusting devices common to 50 said front silicon button and said diaphragm for adjusting the pressure on the front of said silicon granules, in combination with a 55 non-conducting plate on the front of said silicon button.

9. In a transmitter, a body of silicon granules, a support therefor, means in the rear of said body for exerting pressure thereon, 60 a diaphragm resiliently supported at its

outer periphery at the front of said silicon granules, a silicon button contacting with the front of said body of silicon granules, and adjusting devices common to said silicon button and said diaphragm for adjusting the pressure upon the front of said silicon granules.

10. In a transmitter, a body of silicon granules, a support therefor, a front silicon button contacting with the front of said 70 granules, a rear button contacting with the rear of said granules, a pressure exerting device located at the rear of said silicon granules for compressing the latter from the rear, insulation for the front of said silicon button, a diaphragm in front of said silicon button and resiliently supported at its outer edges, and adjusting devices common to said silicon button and diaphragm.

11. In a transmitter, a body of silicon 80 granules, a support therefor, a front silicon button contacting with the front of said granules, a rear button contacting with the rear of said granules, a pressure exerting device located at the rear of said silicon 85 granules for compressing the latter from the rear, insulation for the front of said silicon button, a diaphragm in front of said silicon button and resiliently supported at its outer edges, and adjusting devices common to said 90 silicon button and diaphragm, the latter being composed of a cured skin having liquid glass on each side thereof and a soft iron sheet secured to one of said liquid glass surfaces.

12. In a transmitter, a body composed of a granular variable resistance element, means for supporting the latter, means in the rear of said body for exerting pressure thereon, a front silicon button contacting with the front of said body, a diaphragm, and adjusting devices common to said silicon button and said diaphragm.

13. In a transmitter, a body composed of a granular variable resistance element, 105 means for supporting the latter, means in the rear of said body for exerting pressure thereon, a front silicon button contacting with the front of said body, a diaphragm, and adjusting devices common to said silicon button and said diaphragm, the latter being composed of a cured skin having liquid glass on each side thereof and a soft iron sheet secured to one of said liquid glass surfaces.
